(57) **CLAIM**

The ornamental design for a fare collection machine, as shown and described.

DESCRIPTION

FIG. 1 is a front, top and right side perspective view of a fare collection machine showing our new design;

FIG. 2 is a front, top and left side perspective view thereof;

FIG. 3 is a front view thereof;

FIG. 4 is an enlarged top plan view thereof;

FIG. 5 is a right side view thereof;

FIG. 6 is a left side view thereof;

FIG. 7 is an enlarged view of the portion indicated by line 7-7 in FIG. 1;

FIG. 8 is an enlarged view of the portion indicated by line 8-8 in FIG. 2;

FIG. 9 is an enlarged view of the portion indicated by line 9-9 in FIG. 3;

FIG. 10 is an enlarged view of the portion indicated by line 10-10 in FIG. 5; and,

FIG. 11 is an enlarged view of the portion indicated by line 11-11 in FIG. 6.

The features shown in broken lines in the drawings depict environmental subject matter only and form no part of the claimed design.

1 Claim, 11 Drawing Sheets
